UNITED STATES PATENT OFFICE.

ROBERT SUCZEK, OF PHILADELPHIA, PENNSYLVANIA, ASSIGNOR TO C. H. WHEELER
MANUFACTURING COMPANY, OF PHILADELPHIA, PENNSYLVANIA, A CORPORATION
OF PENNSYLVANIA.

CONDENSATE AND AIR REMOVING APPARATUS.

1,266,344.

Specification of Letters Patent. Patented May 14, 1918.

Application filed December 30, 1916. Serial No. 139,985.

To all whom it may concern:

Be it known that I, ROBERT SUCZEK, a subject of the Emperor of Austria-Hungary, residing in the city of Philadelphia, county 5 of Philadelphia, and State of Pennsylvania, have invented certain new and useful Improvements in Condensate and Air Removing Apparatus, of which the following is a specification.

10 My invention relates to apparatus for removing condensate and air from either a surface condenser or jet condenser, or kindred apparatus.

My invention resides in apparatus of the 15 character referred to in which the condensate pumping means is preferably of the centrifugal type, in which may be employed an auxiliary impeller to preliminarily accelerate the condensate to improve the operation due to the low submergence, with means, 20 such as ejector apparatus, for withdrawing air from the condenser to maintain a vacuum therein, the air being delivered from the ejector apparatus into the condensate between the auxiliary and main impellers, the 25 action of the pump being then to assist in the removal of the air.

And my invention resides further in the 30 employment of double or plural stage ejector apparatus which is employed in starting the apparatus to produce the necessary vacuum within the condenser, the second or later stages of the ejector apparatus being shut off after starting, and the first stage 35 or stages then delivering the air into the condensate pump.

By such construction the double stage apparatus is employed only in starting, and only during such starting period is the steam 40 consumption for the ejector apparatus high. Thereafter only the first or early stages are employed, consuming only relatively small amount of steam, the remainder of the work for raising the pressure of the air to atmospheric being performed by the condensate 45 pump.

My invention resides in the apparatus of

the character hereinafter described and claimed.

For an illustration of some of the various 50 forms my invention may take, reference is to be had to the accompanying drawings, in which:

Figure 1 is a vertical sectional view, some parts in elevation, through apparatus embodying my invention.

Fig. 2 is a sectional view, some parts in elevation, of a modified form of condensate pump and auxiliary structure.

Fig. 3 is a sectional view, some parts in 60 elevation, of a modification of the structure shown in Fig. 2.

Fig. 4 is a vertical sectional view, some parts in elevation, of a modified arrangement in which the pumping mechanism is in 65 two distinct units.

Fig. 4^a is a cross sectional view through a part of Fig. 4.

In Fig. 1, C represents a surface condenser for condensing steam or vapor, especially 70 the exhaust steam from steam power plant or the like. The steam to be condensed enters through the opening 1, and the condensate is delivered through the opening 2 into the passage 3 which delivers to the suction 75 of a centrifugal pump P, the latter comprising the usual volute or discharge casing 4 and the runner or impeller I having the vanes V. The impeller I is secured upon and driven by the shaft 5 driven by any 80 suitable means, as an electric motor or steam turbine. At the entrance to the suction side of the impeller I is provided an auxiliary impeller or fluid moving device I₁ of any suitable type, as a screw propeller, attached 85 at its periphery to and movable with the main impeller I. A third impeller I₂, secured to and rotatable with the main impeller I and delivering between impellers I₁ and I comprises a plurality of radially outwardly extending channels, or it may be a circumferentially continuous impeller, of numerous channels separated by the usual 90 vanes. The vanes of the impeller I₂ are in-

dicated at V_1 and serve to connect the impeller I_2 to impeller I . The suction orifice of the impeller I_2 is the longitudinally extending tube or pipe 6, which has a rotary bearing in the stuffing box 7, the tube 6 communicating with the chamber 8.

Communicating with the vapor space of the condenser C is the pipe 9 through which is drawn air or non-condensable gas into the 10 ejector E of any suitable type, to which elastic motive fluid, as steam, is delivered, the steam emitted from the ejector nozzle entraining the air delivered through the pipe 9, the mixture passing through the pipe 15 10, controlled by valve 11, to the second stage 15 ejector E_1 which delivers the air and steam through the member 12. Branching from the pipe 10 is a pipe 13, controlled by valve 14, communicating with the aforementioned 20 chamber 8.

The ejectors E and E_1 may be of any of the types disclosed in co-pending application Serial Number 179,859, filed July 11, 1917, though my invention is not limited by the 25 character of ejectors employed.

The operation is as follows:

In starting the system, the valve 14 is first closed, and the valve 11 opened; the ejectors E and E_1 are then started by supplying 30 them with steam in the usual way, whereupon the air is withdrawn from within the condenser C, and a suitable degree of vacuum produced. The first ejector E steps up the pressure of the air or gas through a suitable 35 range, as for example, from 29 inches of vacuum to, say, 24 inches of vacuum, while the second ejector E_1 raises the pressure from, say, 24 inches of vacuum to or above atmospheric pressure or other suitable 40 pressure. The desired vacuum in the condenser C having thus been produced and the centrifugal pump having been brought up to speed, valve 14 is first opened and then valve 11 closed, and the steam supply to 45 the ejector E_1 discontinued.

The steam condensed into water, or condensate, passes through the opening 2 and finds a level more or less approximate the level indicated by the line 15, and is accelerated by the impeller I_1 , and moved into the impeller I , which latter further accelerates the liquid and delivers it at higher pressure into the discharge casing 4, from which it is delivered to any suitable point or device. 55 By this coöperation of the impellers I_1 and I an effect is produced which is equivalent to increasing the submergence of the main impeller I , the submergence being well understood to be the distance between the condensate level 15 and the axis or center of the impeller I . That is to say, by employment of the preliminary or auxiliary impeller I_1 the impeller I is working to better advantage in that the liquid at the entry to the

impeller I has been preliminarily accelerated 60 by the impeller I_1 , a condition similar to that obtaining when the submergence of the impeller I is substantially greater than that corresponding with the distance between the center of the impeller I and the condensate 70 level 15.

Simultaneously the ejector E is removing air from the condenser C and delivering it with the steam employed in the ejector through the pipe 13 and valve 14 and into 75 the casing 8, from which it passes into the suction 6 of the third impeller I_2 , which accelerates the mixture by centrifugal action and raises its pressure and delivers it between impellers I_1 and I into the channels of 80 the main impeller I between neighboring vanes V thereof, the condensate moved by the impeller I entraining the air and moving it outwardly with the condensate to the discharge casing 4 at any suitable pressure, 85 as atmospheric pressure or higher.

In Fig. 2 the condensate pump P again comprises the main impeller I having the vanes V , driven by the shaft 5. Within the impeller I is disposed the auxiliary impeller 90 I_1 secured upon the shaft 5 and having the vanes V_1 , the suction 6 of the impeller I_1 communicating with the chamber 3 receiving the condensate from the condenser, not shown. The impeller I is supported and secured upon the impeller I_1 by means of the spaced ribs 16 resembling the spokes of a wheel.

From the ejector apparatus, not shown, connection is made at 17 through the air 100 and steam conducting tubes 18 to the annular chambers 19 on opposite sides of the impeller I . Pipes 20, delivering preferably live steam from any suitable source, communicate with the annular chamber 21. On 105 each side of the impeller I , with suitable circumferential spacing, is provided a plurality of steam nozzles 22 delivering across the chambers 19 and through the spaces between the ribs 16 into the suction side of the 110 impeller.

The condensate is first accelerated by the auxiliary impeller I_1 and delivered thereby into the free space between the periphery of the impeller I_1 and the inner edges of the 115 vanes V of the main impeller I , and from such space is moved and further accelerated and raised in pressure by the main impeller I and delivered into the discharge casing 4, the impeller I being preferably so constructed that it preliminarily accelerates the condensate without increasing its pressure. 120

Simultaneously with the flow of the condensate through the impellers I_1 and I as described, the steam nozzles 22 are operating 125 to carry the mixture of steam and air delivered by the pipes 18 into the space between the impellers I_1 and I , where the mix-

ture is entrained by the condensate and delivered thereby into the discharge casing 4 at at least atmospheric pressure.

The ribs 16 may be so formed as to in effect constitute vanes which assist in the movement of the vapor and air delivered by the pipes 18 into the condensate.

In Fig. 3 double stage compressing apparatus, comprising the ejectors E and E₁ in series, deliver air from the condenser through the tubes 18, as described in connection with Fig. 2. In this case, however, the ribs 16 are omitted and the vanes V₂ and V of the impellers I₁ and I respectively, are integral and continuous from the inner edge 23 to the outer edge 24.

The operation is substantially the same as described in connection with Fig. 2, the impeller I₁ preliminarily accelerating the condensate, which is then further accelerated and raised in pressure by the impeller I, the vapor and air mixture being delivered into the condensate while passing from one impeller to the other.

In Fig. 4 a plural impeller arrangement is again shown. In this case the condensate from the condenser is delivered through the passage 3 to the suction or intake of the preliminary impeller I₁, which is driven by the shaft 5 and accelerates the condensate and simultaneously raises its pressure, the condensate being delivered from the discharge casing 4 through the pipe 25 to the suction of the second or main impeller I also driven by the shaft 5, which further accelerates the condensate and delivers it at higher pressure to the discharge casing 4. Disposed within the impeller I is the stationary rose or plural channel device 26, shown in cross section in Fig. 4*, and comprising the channels 27, of any suitable number. With the channels 27 of the members 26 communicates the passage or pipe 28 in communication with the ejector E.

The ejector E, single or multiple stage, withdraws air from the condenser, whose condensate is delivered to the passage 3, and the mixture of air and steam from the ejector E is delivered through the pipe 25 through the rose 26 into the impeller canals, masses of air and vapor alternating therein with masses of condensate and delivered thereby at higher pressure, at least atmospheric pressure, into the casing 4. The condensate delivered by the pipe 25 to the impeller I reaches the intake of the impeller I through the spaces 29, Fig. 4*, between the channel forming members 27.

Pursuant to requirement for division, some of the subject matter herein disclosed is claimed in my divisional application Serial Number 210,654, filed January 7, 1918. Certain of the subject matter herein disclosed and claimed is disclosed in my copending ap-

plications Serial Number 167,061, filed May 65 7, 1917, and Serial Number 207,744, filed December 18, 1917.

What I claim is:

1. The combination with a condenser, of pumping means for removing condensate comprising a submerged auxiliary impeller, a main impeller, said auxiliary impeller delivering condensate under pressure in dense liquid form to said main impeller, and means delivering air from said condenser into the condensate between the auxiliary and main impellers.

2. The combination with a condenser, of pumping means for removing condensate comprising submerged auxiliary and main impellers, and means for delivering air from the condenser to the condensate between the auxiliary and main impellers.

3. The combination with a condenser, of pumping means for removing condensate comprising a submerged auxiliary impeller, a main impeller, said auxiliary impeller delivering condensate under pressure in dense liquid form to said main impeller, an ejector for withdrawing air from said condenser, and means for conducting the air removed by said ejector into said condensate between the auxiliary and main impellers.

4. The combination with a condenser, of pumping means for removing condensate comprising submerged auxiliary and main impellers, means for extracting air from said condenser, and means for conducting the extracted air into said condensate between said auxiliary and main impellers.

5. The combination with a condenser, of a condensate-removing pump, plural stage ejector apparatus for withdrawing air from said condenser and raising it in pressure, means for discontinuing operation of a later stage of said ejector apparatus, and means for thereafter conducting the air removed from said condenser into said condensate pump.

6. The combination with a condenser, of a centrifugal condensate-removing pump, plural stage ejector apparatus for withdrawing air from said condenser and raising it in pressure, means for discontinuing operation of a later stage of said ejector apparatus, and means for thereafter conducting the air removed from said condenser into an impeller of said condensate pump.

7. The combination with a condenser, of pumping means for removing condensate comprising a submerged auxiliary impeller delivering to a main impeller, plural stage ejector apparatus for withdrawing air from said condenser, means for discontinuing action of a later stage, and means for there- after conducting the air removed from the condenser into the condensate between said auxiliary and main impellers.

8. The combination with a condenser, of a condensate-removing pump comprising a submerged auxiliary impeller delivering to a main impeller, a third impeller delivering into said main impeller, and an air connection from said condenser into the suction of said third impeller.
9. The combination with a condenser, of a condensate-removing pump comprising a submerged auxiliary impeller delivering to a main impeller, a third impeller delivering into said main impeller beyond said auxiliary impeller, and means for extracting air from said condenser delivering into said third impeller.
10. The combination with a condenser, of a condensate-removing pump comprising a submerged auxiliary impeller delivering to a main impeller, a third impeller delivering into said main impeller beyond said auxiliary impeller, and an ejector removing air from said condenser and delivering the same into said third impeller.
11. The combination with a condenser, of a centrifugal condensate-removing pump having an impeller, another impeller delivering into said impeller, and an air connection from said condenser into the suction of said other impeller.
12. The combination with a condenser, of a centrifugal condensate-removing pump having an impeller, another impeller delivering into said impeller, and means for extracting air from said condenser delivering into the suction of said other impeller.
13. The combination with a condenser, of a centrifugal condensate-removing pump having an impeller, a condensate connection from said condenser to said impeller, another impeller whose suction inlet extends through and to the exterior of said condensate connection, and an air connection from said condenser to the suction inlet of said other impeller.
14. The combination with a condenser, of a centrifugal condensate-removing pump having an impeller, a condensate connection from said condenser to said impeller, another impeller whose suction inlet extends through and to the exterior of said condensate connection, and means for extracting air from said condenser and delivering it into the suction inlet of said other impeller.
15. The combination with a condenser, of a centrifugal condensate-removing pump, a condensate connection from said condenser to said pump, a tubular member rotating with the impeller of said pump and extending to the exterior of said condensate connection, a chamber with which said tubular member communicates, and an air connection from said condenser to said chamber.
16. The combination with a condenser, of a centrifugal condensate-removing pump, a condensate connection from said condenser to said pump, a tubular member rotating with the impeller of said pump and extending to the exterior of said condensate connection, a chamber with which said tubular member communicates, and means for extracting air from said condenser and delivering it into said chamber.
17. The combination with a condenser, of an impeller, a pump casing inclosing said impeller, a tubular suction inlet for said impeller extending to the exterior of said casing, a chamber exterior to said pump casing with which said tubular extension communicates, and means for conducting air separately from the condensate from said condenser to said chamber.
18. The combination with a condenser, of a centrifugal condensate-removing pump, a tubular member rotating with the impeller structure of said pump and extending to the exterior of said pump, a chamber with which said tubular member communicates, a means for conducting air separately from the condensate from said condenser to said chamber, the inner end of said tubular member communicating with said impeller structure.
19. The combination with a condenser, of a centrifugal condensate removing pump, a connection for delivering condensate from said condenser to said pump, a tubular member rotatable with the impeller structure of said pump and extending to the exterior thereof, a chamber with which said tubular member communicates, an air connection from said condenser to said chamber separate from said first named connection, and an ejector for removing air from said condenser and delivering it through said air connection into said chamber.
20. Centrifugal water and air removing apparatus comprising impellers having independent suctions, means for delivering air to the suction of one of said impellers, means for delivering water to the suction of another of said impellers, said one impeller increasing the pressure of the air and delivering it into said other impeller.
21. Centrifugal water and air removing pump structure comprising a pump casing, impellers in said casing having a common discharge, separate suctions for said impellers, means for conducting air to the suction of one of said impellers, and means for conducting water to the suction of another of said impellers, said one of said impellers delivering the air acted upon thereby into said other impeller.
22. The combination with a condenser, of centrifugal air and water removing apparatus comprising impellers having independent suctions, means for connecting the suction of one of said impellers with the air space of

said condenser, means for conducting condensate from said condenser to the suction of said other impeller, said one impeller increasing the pressure of the air and delivering it into the water acted upon by said other impeller.

23. The combination with a condenser, of centrifugal air and water removing apparatus comprising impellers having independent suctions, means for removing air from said condenser and delivering it at higher

pressure into the suction of one of said impellers, means for conducting condensate from said condenser to the suction of another of said impellers, said one impeller increasing the pressure of the air and delivering it into said other impeller. 15

In testimony whereof I have hereunto affixed my signature this 28th day of December, 1916.

ROBERT SUCZEK.
